GASOLINE DISPENSER

Coates F. Bateman, Paul A. Mankin, and Edward L. Copony, Salisbury, Md., and Raymond A. Smith, Bradford Woods, and Glenn W. Monigle, Wexford, Pa., assignors to Symington Wayne Corporation, Salisbury, Md., a corporation of Maryland

Original application Apr. 4, 1961, Ser. No. 64,662. Divided and this application Feb. 2, 1962, Ser. No. 69,030

Term of patent 14 years

(Cl. D52—2)

FIG. 1 is a front elevational view of a gasoline dispenser showing one embodiment of our new design;

FIG. 2 is a side elevational view thereof with the opposite side being substantially the same in appearance;

FIG. 3 is a front elevational view of another embodiment of our new design the sides of which are substantially the same in appearance as FIG. 2;

FIG. 4 is a front elevational view of a further embodiment of our new design; and

FIG. 5 is a side elevational view of one side of the embodiment shown in FIG. 4 with the opposite side being substantially the same in appearance but without the fittings.

The rear views in elevation of all of the described

embodiments are identical with the illustrated front views in elevation.

This application is a division of our earlier copending application S.N. D. 64,662 filed April 4, 1961.

We claim:

The ornamental design for a gasoline dispenser, as shown and described.
